INCINERATOR

Joseph K. Blum, Scarsdale, Roger G. Blum, New York, and Donald J. Blum, Scarsdale, N. Y., assignors to Burnwell Incinerator Corporation, New York, N. Y., a corporation of New York

Application January 7, 1950, Serial No. 137,352

6 Claims. (Cl. 110—18)

1

This invention relates to improvements in incinerator installations in buildings, and in particular to a novel type of incinerator furnace for such an installation.

The invention relates specifically to the "chute" type of incinerator which is the type used in apartment houses and other buildings in which refuse may be inserted through doors on each floor and dropped into a chute which leads directly to a furnace chamber in the basement.

The conventional incinerator furnace of this type is essentially a boxlike structure having a grate at the bottom thereof on which the garbage and other refuse comes to rest and accumulates. The furnace is also provided with various access doors for removing ashes, throwing in cellar rubbish, etc. One or more of these access doors is generally used as an air inlet opening. The refuse is usually allowed to accumulate where it drops upon the grate and is ignited at various times. The gases of combustion pass up to the outlet or chimney on the roof through the same flue or chute down which the refuse is dropped. Sometimes a duplex but interconnecting flue is used to separate partly the descending refuse from the ascending gases.

A conventional incinerator of this type possesses certain disadvantages. For instance, the refuse to be burned which is normally a mixture of garbage and rubbish in varying proportions, may have such a great moisture content that ignition is made difficult, if not impossible. If the mixture has a high content of moist garbage it will tend to burn slowly; while if it contains a large amount of dry rubbish such as paper or wood, it will tend to burn quickly. If the mixture is left to smolder, the gases emitted have an extremely disagreeable odor which permeates the atmosphere around the building in which the incinerator is installed. Since these gases pass through the single incinerator chute, they also sometimes tend to seep through the incinerator doors on each floor and spread the disagreeable odor to the respective apartments or lofts.

It is generally recognized that a minimum temperature of 1000° F. to 1200° F. is needed to decompose the emitted gases and render them odorless. This minimum temperature is not often attained in the conventional incinerator of the aforementioned type. It has been attempted to solve this problem by using auxiliary fuel in the incinerator furnace in order to dry moist refuse and properly ignite the same. The conventional incinerator construction, however, makes necessary a large supply of such fuel and is unecono-

2

nomic, and fails to meet the full need for odorless and nuisance-free incineration.

Another and equally disagreeable characteristic of the conventional furnace is the tendency of light ashes, charred bits of paper, and other light debris to rise through the chute with the hot combustion gases. This debris is raised to the roof and discharged about the neighborhood. Large mesh screens are often inserted at the top of the chutes, being generally required by local ordinance, but these screens are not effective in trapping small bits of refuse. A fine mesh screen would of course stop most of these small bits, but such a screen would interfere with the draft through the incinerator furnace.

It is the principal object of this invention to provide an incinerator furnace in which the refuse and the combustion gases are subjected to an auxiliary flame regulated to maintain a desired furnace temperature which is sufficient to cause the refuse to burn thoroughly and is also sufficient to cause the combustion gases to be decomposed.

Another object of the invention is the provision of an incinerator furnace in which the combustion gases are caused to take a devious course through the furnace to the flue or chute, past baffles and checkerwork in order to insure complete combustion of the gases, as well as to cause the major amount of ash to be deposited before it can be carried up the flue or chute. For this purpose, the incinerator furnace is designed to prevent the combustion gases from flowing directly upward to the flue. Instead, the gases are caused to follow a path through a by-pass to the flue.

Other objects and advantages of the invention will be readily apparent in the course of the following specification when taken in connection with the accompanying drawings which illustrate several applications of the invention which are presented by way of illustration and not in a limiting sense.

Fig. 1 is a vertical section showing an incinerator furnace constructed according to the invention and a portion of the flue or incinerator chute communicating therewith; and

Fig. 2 is a fragmentary cross sectional vertical sectional view, taken at right angles to Fig. 1 and showing the nozzle in elevation.

With specific reference to Fig. 1, the incinerator shown therein comprises an incinerator furnace designated generally by the reference numeral 10. The incinerator also has the usual flue or chute 11 extending vertically the entire height

of the building and communicating with a chimney or other outlet (not shown) at the top of the building, and with the incinerator furnace 10. The furnace 10 and flue 11 as well as the other portions of the incinerator have the usual inner walls 12 made of fire brick, and outer walls 13 made of ordinary brick or other suitable material.

The flue or chute 11 has a number of chute doors 14, which open thereinto, these doors 14 being located vertically, one above the other, and one door 14 being located on each floor of the building. For convenience, only one of these doors 14 is shown in the drawings. When the occupant of any floor wishes to dispose of garbage or rubbish, he opens the respective door 14 and drops the refuse down the chute 11 into the furnace 10. This refuse R lands upon, and is retained by a grate 15 which is horizontally secured in spaced relation to the bottom surface of the furnace between the side wall of said furnace and a partition wall 16. The garbage and rubbish R accumulates on this grate 15 as shown in the drawings.

The partition wall 16 separates a lower portion of the furnace interior from the refuse resting on the grate 15. This separated lower portion 17 serves as a gas mixing and combustion chamber. The furnace 10 has a baffle wall 10a adjacent said chamber 17 which is provided with one or more gas passages 18 extending through checker-work 19. The gas passages 18 communicate with an uptake and connecting flue 20 which serves as a by-pass for returning the combustion gases to the main flue or chute 11. The uptake flue 20 is located adjacent the baffle wall 10a of the furnace and is connected by a passageway in the form of a pipe 20a, to the main flue or chute 11 above the juncture of the flue 11 with the top of the furnace 10. The opening in the flue or chute 11 with which the pipe 20a communicates, may optionally be provided with a screen 32 which prevents the refuse dropped down flue 11 from lodging in the pipe 20a or flue 20.

The furnace 10 is also provided with an externally-located oil burner (not shown) whose nozzle 21 extends within the interior of the furnace 10 at a suitable location in which the flame emitted by the nozzle 21 will sufficiently cover the gas mixing and combustion chamber 17 as well as the refuse R which has accumulated on the grate 15. The fuel burner may burn gas or oil, and is preferably thermostatically controlled to maintain any desired furnace temperature.

An air blower 22 is located exteriorly of the furnace 10. The blower 22 feeds through a pipe 23 to a plenum chamber 24 located adjacent the bottom of the chute or flue 11. The plenum chamber 24 has a nozzle 25 which extends through the wall of the flue or chute 11 and communicates with the interior of said flue 11. The nozzle 25 is preferably as wide as the flue 11, so that it extends the full width of the flue 11.

Incinerator flues vary in size but are generally about twenty inches to thirty inches square. The furnaces normally have a larger area.

The chute or flue 11 is optionally provided with a damper 26 for controlling the draft, if necessary. The provision of such a damper will depend upon the requirements of the particular building in which the installation is to be made.

The furnace is provided with the usual access or feed openings, some examples of which are shown in the drawings. These openings have doors which may be opened or closed when re-

quired. For example, the furnace 10 has an air inlet opening 27 located below the grate 15, a firing opening 28 located above the grate 15, an access opening 29 located adjacent the bottom 5 of the gas mixing and combustion chamber 17, and an access opening 30 located adjacent the bottom of the uptake flue 20.

At suitable times as refuse R accumulates on the grate 15, the burner is fired and the flame emitted by the nozzle 21 will thoroughly dry said refuse R. Air forced from the blower 22 and out the nozzle 25 is directed down the lower end 10 of the flue 11 and into the interior of the furnace 10. This air current forms an effective shield

15 which prevents the combustion gases from rising directly up the flue 11 from the furnace 10. As the air enters the furnace 10 it is heated by the flame and becomes a source of combustion air to assist in the effective combustion of the refuse R. Additional air if required can be introduced 20 through the air inlet opening 27, as indicated in the drawings, or through any of the other openings in the furnace 10.

The cold air entering the furnace interior 25 creates a circuitous air current, the direction of which is indicated by the arrows in Fig. 1. The heated air mixes with the burning gases and is carried over the top of the partition wall 16, and into the gas mixing and combustion chamber 17. During its travel, and when it has 30 entered the chamber 17, the combustion gases are subjected to the flame emitted by the burner nozzle 21 and these gases are decomposed and rendered odorless. This is possible since the 35 combustion gases are carried across the furnace 10 instead of being allowed to escape directly up the flue 11 as in conventional incinerators.

The combustion gases and heated air leave the interior of the furnace 10 and enter the uptake and connecting flue 20 through the gas passages 18. An appreciable portion of any small 40 bits of ash or other waste particles carried by the current will encounter the checker-work 19 in the baffle wall 10a and be deposited at the bottom of the gas mixing and combustion chamber 17. The lower portion of said chamber 17 thus acts as a catch pocket 31 for this debris. The debris may be removed, when desired, 45 through the access door 29.

The air current then flows through the uptake flue 20 and the connecting pipe 20a and enters the main flue or chute 11 at a point above the nozzle 25 at which the current originates. Thus the air current carries the combustion gases 50 through a devious course in the furnace interior, and then through a by-pass to the flue or chute 11 through which it will rise to the roof, because of chimney draft action.

While preferred embodiments of the invention 55 have been shown and described herein, it is obvious that numerous additions, alterations, and omissions may be made in the invention without departing from the spirit and scope thereof. The invention is not intended to be limited to the specific structure of the incinerator nor the specific location or construction of the means for creating the draft. Obviously, these factors will vary with different field conditions and types of installations.

70 What is claimed is:

1. In an incinerating apparatus having a combustion chamber and a common upwardly extending feeding and discharge flue communicating with one end of the combustion chamber, a by-pass leading from the other end of the com-

bustion chamber to said flue above the lower end of the latter, said by-pass including a down-flow portion within the rear end of the combustion chamber and an upflow portion rearward of the down-flow portion with the two portions located on opposite sides of a vertical wall of the by-pass common to the combustion chamber and the two by-pass portions with the lower portion of the wall perforated to afford communication between the portions, a discharge nozzle opening into the lower end of said flue between said by-pass and the bottom of the flue and extending transversely the entire width of said flue in a downwardly inclined direction, means operatively associated with said nozzle for delivering an external air stream under pressure into said nozzle and within the lower portion of said flue, the stream of air intersecting the length of such lower end of the flue and extending across the width of said flue and moving downwardly into the combustion chamber toward the front of the zone of incineration and substantially into contact with such incineration content to combine with and augment the products of combustion en route to the down-flow portion of the by-pass, the portion of the stream traversing such lower end of the flue forming a barrier against the direct escape of products of combustion from the combustion chamber to the flue.

2. In an incinerating apparatus having a combustion chamber and a common upwardly extending feeding and discharge flue communicating with one end of the combustion chamber, a by-pass leading from the other end of the combustion chamber to said flue above the lower end of the latter, said by-pass including a down-flow portion within the rear end of the combustion chamber and an up-flow portion rearward of the down-flow portion with the two portions located on opposite sides of a vertical wall of the by-pass common to the combustion chamber and the two by-pass portions with the lower portion of the wall perforated to afford communication between the portions, a discharge nozzle opening into the lower end of said flue between said by-pass and the bottom of the flue and extending transversely the entire width of said flue, said nozzle being directed transversely toward the other side of said flue, means operatively associated with said nozzle for delivering an external air stream under pressure into said nozzle and within the lower portion of said flue, the stream of air intersecting the length of such lower end of the flue and extending across the width of said flue and moving downwardly into the combustion chamber toward the front of the zone of incineration and substantially into contact with such incineration content to combine with and augment the products of combustion en route to the down-flow portion of the by-pass, the portion of the stream traversing such lower end of the flue forming a barrier against the direct escape of products of combustion from the combustion chamber to the flue.

3. In an incinerator having a combustion chamber and a common upwardly extending feeding and gas discharge flue communicating with one end of the combustion chamber, a by-pass conduit communicating at one end with said combustion chamber and at the other end with said flue, a discharge nozzle opening into the lower end of said flue between said by-pass

conduit and the bottom of the flue and extending transversely the entire width of the flue, and means operatively associated with said nozzle for introducing a current of air through said nozzle, said nozzle being directed in a downwardly-inclined direction to produce an air stream which flows downwardly across the bottom of said flue and into the furnace.

4. In an incinerator having a combustion chamber and a common upwardly extending feeding and gas discharge flue communicating with one end of the combustion chamber, a by-pass conduit communicating at one end with an opening in said combustion chamber and at the other end with said flue, a discharge nozzle opening through one wall of said flue at the lower end thereof between said by-pass conduit and the bottom of the flue and extending transversely the entire width of the flue, and means operatively associated with said nozzle for introducing a current of air through said nozzle, said nozzle being directed in a downwardly-inclined direction toward the bottom end of the opposite wall of said flue, said air-introducing means having sufficient force to create a shield of air across the lower end of said flue operative to prevent the passage of combustion gases from the furnace from rising vertically directly up the flue, and to cause the air to pass downwardly from the flue into the interior of said furnace.

5. An incinerator assembly according to claim 4 in which the combustion chamber opening is located at the end of the combustion chamber opposite said flue, whereby to cause said air current to traverse the length of the incinerator before entering said by-pass conduit through said furnace opening.

6. In an incinerating apparatus having a combustion chamber and a common upwardly extending feeding and gas discharge flue which communicates with one end of the combustion chamber, a by-pass conduit communicating with the other end of said combustion chamber and opening into said flue above the lower end thereof, a fuel burner in said combustion chamber, an air inlet conduit opening into said flue between said by-pass conduit opening and the bottom of the flue, said air inlet conduit extending transversely substantially the entire width of the flue and directed transversely toward the other side of said flue, and means operatively associated with said inlet conduit for introducing a current of air through said air inlet conduit, said current of air covering the area of the flue and striking the opposite wall of the flue to form an air seal across the lower end of the flue and directed to prevent the escape of hot gases from said combustion chamber directly up said flue.
